UNITED STATES PATENT OFFICE.

JAMES E. EVANS, OF LOS ANGELES, CALIFORNIA.

GAS GENERATOR AND BURNER.

1,274,024.

Specification of Letters Patent. Patented July 30, 1918.

Application filed March 12, 1918. Serial No. 222,033.

To all whom it may concern:

Be it known that I, JAMES E. EVANS, a citizen of the United States, residing at Los Angeles, in the county of Los Angeles and State of California, have invented certain new and useful Improvements in Gas Generators and Burners, of which the following is a specification.

My invention relates to heating apparatus and has for its objects to provide an apparatus which may be placed in a stove or furnace for generating gas from liquid fuel and burning said gas as a fuel in said stove or furnace.

15 These and other objects I accomplish with the apparatus illustrated in the accompanying drawings in which similar letters and numerals of reference indicate like parts throughout the several figures and as described in the specification forming a part of this application and pointed out in the appended claims.

In the drawings in which I have shown a substantial embodiment of my invention, 20 Figure 1 is a side elevation of the apparatus, parts cut away. Fig. 2 is a plan view of the same, parts cut away. Fig. 3 is a transverse section on line 3—3 of Fig. 2.

The present invention is a compact apparatus which may be placed in the fire box of a stove or furnace and wherein a low grade liquid fuel such as crude petroleum, or distillate may be forced by compressed air into a gas generator wherein said liquid fuel is converted into a gas, and said gas and the required amount of air is then conducted into two parallel spaced burners positioned above the generator where said gas from said liquid fuel is burned, and some of 30 said gas is directed into another burner positioned beneath the generator to supply heat for generating the gas. I also provide as a part of my apparatus means to prevent the accumulation of soot therein. My apparatus 35 consists of a fuel tank A which is operatively connected with an air pump B by means of which compressed air is provided to force the liquid fuel, such as distillate, from said tank A through a small 40 pipe C into one end of the generator D. The said generator consists of a cylinder 1, which is externally threaded on one end and internally threaded at the other end. In the 45 internally threaded end is screwed the needle valve seat 2 which reduces the flow of gas through the generator and provides a seat 50 for the valve. On the externally threaded end of said generator is screwed the valve stem elbow 3. The said elbow 3 is externally threaded on one end to receive the 55 union coupling of the pipe C and the other end is internally threaded to receive the threaded portion of a valve stem 4. The said valve stem 4 is carried in said generator, and has a portion threaded to engage the 60 threads in the said valve stem elbow 3 and has the free end inclined or beveled to a point to fit in the seat 2. The burner consists of two parallel spaced apart tubular 65 burner members 5 which are mounted on 70 the inverted U-shaped supports 6, and each has a plurality of transverse saw cuts 7 therein to provide gas jets and by cutting only partially across said members and on the outer sides of each the gas is directed 75 up and away from said burner members 5 in order that when the gas is ignited the flame will not injure the other parts of the apparatus. A U-shaped conduit 8 having one end 80 opening into a divider case 9 is provided to direct the gas from said generator D into both of said burner members 5 and break up the flow of the gas so that it will flow into said members 5 with but a slight current. The 85 said divider case 9 is secured on one end of the said members 5. In the other end of one of said burner members 5 is connected the pipe 10 through which a limited amount of gas is supplied to a generator burner 11 positioned under the said generator D. The 90 said generator burner 11 has a plurality of holes 12 in one side to allow gas to escape for burning to heat the generator D. An asbestos mat plate 13 is fastened on said generator burner parallel therewith by 95 which the initial heat may be provided to start the apparatus. Water is supplied through the valves 14 into said valve stem elbow 3 when desired to form steam to clean the apparatus from any accumulation of soot 100 therein.

The operation of my apparatus is as follows:

With the fuel provided in the tank A and air pressure supplied by the pump B, the 105 initial heat is provided by saturating the said asbestos mat 13 with alcohol or any volatilizing fuel and lighting the same. When the generator D is hot the liquid fuel therein will be turned into gas and by turning the 110 valve stem 4 the desired amount of gas will escape through the needle valve as made up

by the seat 2 and point of the stem 4. The escaping gas will be directed through the U-shaped conduit 8, the divider case 9 and into the burner members 5 and pass out through the saw cuts 7. The gas will be ignited by the flames from the mat 13, and to continue the supply of gas after the initial fuel is burned out of the said mat 13, some of the gas from one of the burner members 5 will be directed through the pipe 10 into the generator burner 11 and escape through the holes 12. When the gas from said holes 12 is in flame it will provide the heat required to continue the generation of gas in said generator D. Before the gas from the holes 12 is lighted the said mat 13 is turned on its axis, which is the said pipe 10 at one end and a pin 15 in the other end of said generator burner 11, to the position shown in dotted lines in Fig. 3. Should soot accumulate at any time in the apparatus it may be eradicated by a small quantity of water supplied within the generator D through the valve 14, which water is turned into steam in said generator and mingling with the gas will clean the apparatus of any soot.

Having thus described my invention I desire to secure by Letters Patent and claim:

1. In a gas generator and burner the combination of a cylindrical generator; a needle

valve to regulate the flow of gas therefrom; a generator burner below said generator; two spaced apart main burners above said generator; a conduit to direct the gas from said generator into said main burners; a 35 mat below said generator on which to burn liquid fuel to provide the initial gas; a pipe from one of said spaced apart main burners to said generator burner; and means to supply a limited amount of water into said generator. 40

2. In a gas generator and burner the combination of a cylindrical generator; a needle valve to regulate the flow of gas therefrom; a generator burner below said generator; two 45 spaced apart main burners above said generator; transverse saw cuts partially across said main burners; a U-shaped conduit and bifurcated to direct the gas from said generator into said main burners; a mat below said 50 generator on which to burn liquid fuel to provide an initial gas; a pipe connecting one of said spaced apart main burners and said generator burner; and a valve controlled 55 water pipe to supply a limited amount of water into said generator.

In testimony whereof I have affixed my signature.

JAMES E. EVANS.
